UNITED STATES PATENT OFFICE.

JUSTUS A. TRAUT, OF NEW BRITAIN, CONNECTICUT.

DESIGN FOR A LEVEL FRAME OR BLOCK.

SPECIFICATION forming part of Design No. 25,130, dated February 4, 1896.

Application filed October 8, 1894. Serial No. 525,209. Term of patent 7 years.

To all whom it may concern:

Be it known that I, JUSTUS A. TRAUT, a citizen of the United States, residing at New Britain, in the county of Hartford and State of Connecticut, have invented and produced a new and original Design for a Level Frame or Block, of which the following is a specification, reference being had to the accompanying drawing, which represents my design applied to a level-frame.

In the drawing, accompanying and forming part of this specification, the figure thereof represents a side elevation of a level frame or block showing this design.

This design relates to level frames or blocks; and the leading feature thereof consists in the representation of a level frame or block having a number of annular and semiannular bands represented thereon.

In the drawing, A represents a level frame or block, which is rectangular in cross-section and in its general contour.

2 represents an outer annular band circumscribed about and concentric with a second or inner beveled annular band, 3, the inner line of which band 3 encircles an open space 4, (shown as in or about the middle of the level frame or block,) although, as is obvious, it may be in any desired part of the block.

5 represents an outer semiannular band 30 circumscribed about and concentric with a second or inner beveled semiannular band, 6, the inner line of said semiannular band 6 semiencircling an open space 7, and said semiannular bands having their diameters 35 substantially in the line of one of the edges of the level frame or block A.

I claim—

The design for a level frame or block, substantially as herein shown and described.

JUSTUS A. TRAUT.
